UNITED STATES PATENT OFFICE

FREDERICK A. HENGST, OF RACINE, WISCONSIN

METHOD OF AND APPARATUS FOR STRAIGHTENING AND SOLIDIFYING ELECTROTYPE PLATES AND THE LIKE

Application filed August 9, 1928. Serial No. 298,580.

The solidifying and straightening of electrotype plates has heretofore been a tedious hand operation requiring extreme care and highly skilled workmen as it is essential that only the proper portions of the plate be worked upon and then only to a predetermined degree. It is, therefore, an object of this invention to provide a device whereby a plate may be treated in a single operation.

10 Another object of this invention is to provide a device of the character described in which the solidifying and straightening of electrotype plates is accomplished independent of manual skill.

15 Another object of this invention resides in the provision of a plurality of individually movable units upon which an electrotype plate is positioned and below which a matrix or stencil, known in the art as a "make-ready", 20 is placed so that when pressure is applied to the plate certain of the units will exert a pressure thereon.

25 And a further object of this invention resides in the provision of a device of the character described having a plurality of cross bars between which a plurality of pressure units are mounted, the units having a connection with the cross bars which permits their restricted longitudinal movement.

30 And a still further object of this invention is to provide a method of straightening and solidifying electrotype plates in which a plate, a matrix and a plurality of individually movable units positioned between the plate 35 and matrix are placed in a press, whereupon pressure is imposed on the plate at points governed by the formation of the matrix.

With the above and other objects in view which will appear as the description proceeds, 40 my invention resides in the novel construction, combination and arrangement of parts substantially as hereinafter described and more particularly defined by the appended claims, it being understood that such changes 45 in the precise embodiment of the herein disclosed invention may be made as come within the scope of the claims.

In the accompanying drawings, I have illustrated one complete example of the physical embodiment of my invention constructed

according to the best mode I have so far devised for the practical application of the principles thereof, and in which:

Figure 1 is an elevational view illustrating an electrotype straightening and solidifying device positioned in a conventional hydraulic press;

Figure 2 is a top plan view of the device removed from the press;

Figure 3 is an enlarged fragmentary perspective view taken through Figure 2 on the plane of the line 3—3;

Figure 4 is an enlarged sectional view illustrating the position of the parts after being subjected to pressure, and

Figure 5 is a perspective view of one of the pressure units.

Referring now more particularly to the accompanying drawings, in which like numerals designate like parts throughout the several views, 5 represents the base of a conventional hydraulic press having a stationary head 6 supported on corner up-rights 7, the head being secured to the up-rights by nuts 8, as is customary. The base 5 is provided 75 with a well in which the plunger 9 of a movable platen 10 is positioned to be raised by hydraulic pressure.

The improved solidifying and straightening device per se consists of a base 11 formed of a plate having the desired size and thickness with its surfaces ground parallel and provided with a chase or frame 12 hinged from one side, as at 13, and consisting of a pair of side members 14 and a pair of end members 15 connected by screws 16.

The side members 14 have their inner edges longitudinally grooved, as at 17, to receive the ends of a plurality of cross bars 18 between which a plurality of individual pressure units 19 are mounted. Each unit 19 is preferably square in cross section and has two opposite sides transversely channeled, as at 20, the channel being of a width greater than the width of the cross bars 18 and of a depth substantially half of the thickness of the cross bars.

In assembling, one side member 14 is detached and a series of units are positioned along one end member 15, a cross bar 18 be-

ing then inserted in the aligned channels of the series of units with one end positioned in the groove 17 of the other side member and a second series of units is positioned with the channels of one side receiving the cross bar. Another bar is then inserted and after the entire space within the frame is filled, the removed side member 14 is secured in position, the plurality of units being thus retained against lateral movement, but permitted a degree of individual or collective longitudinal movement which is governed by the difference in the width of the channels 20 and the cross bars 18.

15 In use, the base plate 11 is placed on the movable platen of the press, as illustrated in Figure 1, and the chase frame thrown back on its hinges, a handle 22 being provided to facilitate this movement and a matrix or "make-ready" 23 is positioned on the plate 11, see Figure 4. The matrix or "make-ready" may consist of a plain sheet of paper of the desired thickness which has portions cut out to represent the weak portions of the plate, or in other words those portions it is desired to leave untouched.

20 To insure the proper positioning of the matrix 23 on the base 11, a pair of depressible guide members 24 arranged at right angles with each other are positioned at one corner of the base plate. Each guide member 24 has a relatively thin blade 25 which normally extends above the surface of the plate to provide stop means against which the adjacent edges of the matrix are engaged.

25 The lower portion of the blade 25 terminates in an enlarged, longitudinal base 26 which is vertically movable in a recess 27 in the base plate, and having one side cut back, as at 28, to provide an overhanging shoulder 29, which, with a similar shoulder 30 extended from a jib member 31 secured in the recess adjacent its other side, provides means against which the enlarged base 26 is yieldably urged by springs 32 confined between the bottom of the recess and pockets in the underside of the enlargement 26. The shoulders 29 and 30 are spaced to permit the blade 25 to move therebetween and the jib member 31 whose major portion 33 extends to the bottom of the recess to, with the cut back portion 28, define a longitudinal channel in which the enlargement 26 and its urging springs are confined, has a lateral flange 34 by which it is secured to the base plate, the top surface thereof being flush with the surface of the plate.

30 It will thus be seen that the guides 24 are readily depressible to permit the upper edges of their blades 25 to be moved flush with the top surface of the plate when the frame is closed over the matrix.

35 With the matrix positioned beneath the plurality of pressure units, it will be readily apparent that the top surfaces of the units

directly above the cut out portions in the matrix will be lower than the upper faces of those above the solid portions of the matrix. This is the position of the parts as illustrated in Figure 4. The upper surface of each pressure unit is provided with a plurality of upwardly extending projections or needles 21 for a purpose to be later described.

40 With the frame closed down over the matrix, an electrotype plate 35 is laid on the pressure units, being properly aligned with the matrix by a second pair of guide members 36 carried by the frame, in vertical alignment with the guides 24. The construction of the guide members 36 is identical to that of the guides 24 and the reference characters directed to the guides 24 are common to both. Pressure is now applied by the press and the units above the cut out portions of the matrix, which portions coincide with the weak portions of the plate or those parts which it is desired not to solidify, have their upper surfaces below that of the remaining units. It is thus evident that only the desired portions of the plate will be subjected to pressure. The formation of the needles or projections on the upper faces prevents spreading of the material of the plate as they provide spaces into which the displaced metal flows when pressure is applied thereto.

45 From the foregoing description taken in connection with the accompanying drawings, it will be readily apparent to those skilled in the art to which an invention of the character described appertains, that I provide a novel means for solidifying and straightening electrotype plates by which an entire plate may be treated in a single operation, in which any desired portion of the plate may be subjected to pressure and in which the application of pressure to a plate does not weaken the same.

50 What I claim as my invention is:

1. In a device of the character described, a plurality of pressure units arranged with their sides abutting to form substantially a plate having parallel normally continuous surfaces, and means engageable with their abutting sides for retaining the units in said position and permitting a degree of unrestricted longitudinal movement with respect to each other.

55 2. In a device of the character described, a plurality of pressure units, retaining bars, and means connecting the units with the bars to permit longitudinal movement of the units with respect to the bars.

3. In a device of the character described, a frame, a plurality of pressure units arranged side by side to completely fill the frame, and means mounting the units in the frame whereby they are permitted a degree of free longitudinal movement.

60 4. In a device of the character described, a stationary cross bar, pressure units, and

means connecting the units with the cross bar whereby they are retained against lateral movement but permitted longitudinal movement.

5. In a device of the character described, a frame, a plurality of cross bars secured in the frame, pressure units mounted between the cross bars with their faces normally forming an unbroken plane, and means connecting the units with the cross bars, whereby they are permitted longitudinal movement but restrained against lateral movement.

6. In a device for straightening and solidifying electrotype plates including a pressure applying means, a plurality of means free to adjust themselves to the variations in a matrix engaging one face of the adjustable plurality of means whereby pressure is applied to an electrotype plate engaging said means at points governed by the variations of the matrix.

7. In a device of the character described, a base plate adapted to receive a matrix, means for facilitating the positioning of the matrix on the plate, a frame adapted to be positioned over the plate, pressure units mounted in the frame, means whereby the units are free to adjust themselves through variations of the matrix, means carried by the frame for facilitating the alignment of an electrotype plate with the matrix, and means for applying pressure to the plate whereby the pressure is exerted at points depending upon the variations of the matrix.

35 8. The herein-described method of straightening and solidifying electrotype plates and the like which consists in positioning a plate and a matrix with a plurality of movable units therebetween in a press and in applying pressure thereto.

9. The herein-described method of straightening and solidifying printing plates which consists in subjecting the printing plate to pressure through a pressure applying member composed of a plurality of individual units, and in providing a matrix engageable with the pressure applying member to select the units through which pressure is to be applied whereby predetermined portions of the plate are subjected to pressure.

10. A device for use in straightening and solidifying printing plates, comprising a base plate, a frame movable over the base plate, a plurality of pressure units arranged side by side to completely fill the frame, means securing the pressure units in the frame whereby the units are permitted individual longitudinal movement, and means on opposite sides of the frame to align a printing plate engaging one face of the pressure units with a matrix engaging their opposite face, whereby pressure may be applied to the printing plate in accordance with the configuration of the matrix.

65 11. The herein-described method of treat-

ing electro-type plates and the like which consists in placing the plate and a matrix having a predetermined co-relation to the plate in a press with a plurality of individual freely movable units therebetween, and in applying pressure thereto.

In testimony whereof I have hereunto affixed my signature.

FREDERICK A. HENGST.
